UNITED STATES PATENT OFFICE.

SAMUEL J. WENTWORTH, OF NEWPORT, KENTUCKY, ASSIGNOR, BY MESNE ASSIGNMENTS, TO UNITED SHOE MACHINERY CORPORATION, OF PATERSON, NEW JERSEY, A CORPORATION OF NEW JERSEY.

CUTTING-MACHINE.

1,279,624.

Specification of Letters Patent. Patented Sept. 24, 1918.

Application filed March 27, 1916. Serial No. 87,018.

To all whom it may concern:

Be it known that I, SAMUEL J. WENTWORTH, a citizen of the United States, residing at Newport, in the county of Campbell and State of Kentucky, have invented certain Improvements in Cutting-Machines, of which the following description, in connection with the accompanying drawings, is a specification, like reference characters 10 on the drawings indicating like parts in the several figures.

This invention relates to machines for cutting out or cutting off the exposed portions of the backing in appliqué work, and 15 is herein illustrated in connection with a machine for ornamenting boots and shoes in the formation of what is known to the trade as "inlaid panel work".

In certain kinds of fancy shoes it is customary to die out ornamental openings in 20 the upper and then, after the lining has been attached to the upper to cut out those portions of the lining which are exposed by the died-out openings in the upper. The 25 openings in the finished shoe thus extend entirely through the upper and lining, and the pattern of the openings becomes conspicuous by reason of the bright colored stockings with which shoes of this type are 30 designed to be worn. The uppers at the edges of the died-out openings are stitched to the lining, thereby forming appliqué work in which the ornamented upper or pattern is appliquéd upon a plain lining.

35 Hitherto it has been customary to cut out the exposed portions of the lining by means of an ordinary knife, the work being done manually; and the general object of the present invention is to produce a machine 40 for performing this operation. According to one feature of the invention the knife reciprocates through an opening in the work support and is angularly movable about an axis located in advance of the 45 cutting edge thereof. In the illustrative machine the knife is mounted for free angular movement about the axis of a guide so that, as the work is moved along with the guide in contact with the edge of an 50 opening in the upper, the knife cuts a registering opening in the lining.

This and other features of the invention, including certain details of construction and combinations of parts will be described in

connection with an illustrative machine and 55 pointed out in the appended claims.

Referring now to the accompanying drawings,—

Figure 1 is an elevation of a machine in 60 which the present invention is embodied;

Fig. 2 is a detail perspective, partly in section, showing a piece of appliqué work being operated upon;

Fig. 3 is a section on the broken line of 65 Fig. 2, the auxiliary support being shown in full, and

Fig. 4 is a perspective showing the knife in operation upon a piece of work.

Figs. 2, 3 and 4 are upon an enlarged scale.

70 Mounted in an overhanging arm 1 of the frame of the machine is a rotary shaft 3 having fast at one end a clutch member 5 and loose at the same end a sliding clutch pulley 7. A bell crank lever 9 pivoted at 75 11 has a brake member 13 at the end of one arm and at the end of the other arm a disk 15 which contacts with the hub of the pulley 7 so that when the bell crank lever is swung in a counter-clockwise direction the clutch pulley 7 is pressed against the clutch member 5 to apply power to the shaft 3 and the brake 13 is swung away from the member 5, and when the bell crank lever 9 is swung in a clockwise direction the 80 clutch pulley 7 is freed from the clutch member 5 and the brake 13 is applied to said last-named member. Normally, as will presently appear, the bell crank lever is held, as shown, in its extreme counter-clockwise position by a link 17 with power applied to the driving shaft 3 and the brake 13 in inoperative position. This link 17 is pivoted at its upper end at 19 to the horizontal arm of the bell crank lever 9 and 85 at its lower end passes through an eye in the end of a work support carrying lever 21 which is pivoted to the frame of the machine at 23, said lever being normally held in the position shown against a stop 90 nut 25 on a rod 27 by a coiled spring 29, the rod passing loosely through the lever as shown. A treadle (not shown) attached to a treadle rod 31 provides means for pulling the forward end of the lever 21 downwardly, 95 and a stop screw 33 furnishes adjustable means for limiting the extent of such movement. A spring 34 engages with its upper

end a nut or collar 35 fast to the link 17 and with its lower end the tail of the lever 21 so that when the treadle attached to the rod 31 is depressed the brake 13 is applied 5 yieldingly.

The forward end of the lever 21 carries a work support in the form of a thimble 37, upon the rim of which the work rests, said thimble having in the center thereof an auxiliary support 39 in the form of an upright cylindrical standard of small cross section the function of which is to support the lining 200 close to the point at which the cutting is being done. A ring-shaped presser foot 41 has an operative lower face which registers with the rim of the thimble 37, said foot being fast to a stem 43 which is adjustably held in a head on the overhanging arm 1 by a set screw 45. This presser foot 10 41 is stationary during the operation of the machine, the stop nut 25 which limits the upward movement of the thimble 37 being so adjusted that the work is not gripped between the foot 41 and the rim of the thimble 15 37, but is loosely held so that the operator may move the work to cause the cutting to take place. The function of the ring-shaped presser foot 41 and the coöperating work supporting rim of the thimble is somewhat 20 analogous to that of an embroidery frame in which a portion of a piece of fabric is held taut over one ring by another ring which fits over the first one. In the present machine it is desirable that the portion of 25 the work which is being operated upon be held as taut as possible but that at the same time the work should be freely movable so that it may be properly manipulated to cause the knife to follow the edge of the 30 opening in the upper 100. Consequently the pressure of the foot 41 on the work is very light. Inasmuch, however, as the work usually operated upon consists of two layers of leather (the upper and the lining), this 35 is sufficient to prevent buckling of the work within the circle of the presser foot and rim. Although the rim of the thimble is the work-support proper since it supports that portion of the work which is being operated 40 upon, the machine is provided with a bed 46 upon which the work may lie. Ordinarily an upper and its attached lining is a comparatively large article so that it is desirable to provide a bed for those portions of it which 45 are not being operated upon.

In order to guide the knife and to grip the lining firmly at a point adjacent the point which is being operated upon by the knife, a guide member 47 is formed on the end of 50 a finger 49 which projects from the base of the presser foot into the center of the circular portion thereof. This guide is of a cross-section approximately equal to that of the auxiliary support 39 and is held against 55 the edge of the opening in the upper while

the work is moved during the cutting operation. The lower end or face of this guide extends below the plane of the operative face of the presser foot 41 and presses the lining against the upper end of the auxiliary support 39 to hold said lining firmly 70 at a point close to the edge of the knife.

The knife 51 is adjustably held between two ears 53 by a pinch screw 55 said ears being part of a collar 57 which is freely revoluble on the lower end of a reciprocatory knife-bar 59. A crank pin on a disk 61 fast to the end of the shaft 3 is connected to a pin on the knife bar 59 by a connecting rod 63 so that the knife is reciprocated continuously as long as power is applied to the driving shaft 3. The axis of the bar 59 upon which the knife is mounted coincides with the axis of the guide 47 and that of the auxiliary support 39; and the blade 75 of the knife, that is its direction of cut, is radial to this axis. The knife may be adjusted toward and from this axis after the pinch screw 55 has been loosened, and is free to swing about this axis nearly three 80 hundred and sixty degrees from contact with one side of the finger 49 to contact with the other side of said finger.

In the operation of the machine a piece of appliquéd work such as that formed by stitching an ornamental upper 100 to a lining 200 is properly placed upon the bed 46 after the lever 21 has been pulled down by depressing the treadle which is attached to the treadle rod 31. The treadle 100 is then released, whereupon the spring 29 raises the work support to cause the sharp point of the knife to pierce the lining and simultaneously, through the bell crank lever 9, starts the reciprocation of the knife. If 105 the operator is skilful, the guide 47 is in contact with the edge of the ornamental opening in the upper at the time the knife pierces the lining. In any event, however, this position may be readily secured by moving the stock slightly. Starting then with the guide 47 in contact with the edge of the opening in the upper and the knife lying alongside said edge, the operator moves the stock in a path determined by the shape 110 of said opening to cause the knife to cut out the exposed portion of the lining. If the knife were not free to swing about the axis of the guide 47 it would be necessary to swing the stock when a curve was encountered, but with the present construction no such swinging movement is imparted to the stock. Considering the illustrated piece of stock in which the opening in the upper is of a general rectangular shape except for 115 the rounded ends, the various positions occupied by the edge 300 during the entire cutting operation are parallel to one another, the knife swinging about its axis when a change in the direction of the cut is 120 125 130

required. As illustrated in Fig. 2 the knife at the time of piercing the lining had its cutting edge facing toward the right. The operator first moved the stock a short distance to the left until the curved end was reached, then diagonally away from himself and to the left until the extreme right-hand end of the opening was reached, then diagonally away from himself and to the right, then momentarily straight to the right until the parts reached the position illustrated in the figure was reached. The remaining directions of movement are indicated by the arrows:—first to the right, then diagonally toward himself and to the right, then diagonally toward himself and to the left, then straight to the left to the point of beginning.

The description of the movement of the work which has been given above is only approximately correct and has been presented to facilitate an understanding of the movement of the knife around the axis of the guide 47. Speaking more accurately, any selected point in the work describes, during the cutting operation, a figure which is practically identical with the outline of the opening in the upper. Of course the figure described by such a point is slightly smaller than the outline of the opening owing to the fact that the guide 47 is not a point but has an appreciable diameter. The actual size of the guide 47, however, is small with the result that the opening cut in the lining is co-extensive with the opening in the upper. The reason why the knife 51 always alines itself with its edge presented in a direction opposite to that in which the work is being moved can perhaps be understood by considering how it would present itself if the work remained stationary and the knife bar 59 were moved in such a manner that its axis traveled in contact with the edge of the opening in the upper. In such a case the knife, since it is pivoted about the said axis, would swing in response to every change in direction of movement of the stem 59 much as a freely movable rudder on a boat would swing if the boat were steered by some means not connected with such rudder. The angular movements of the knife in the present machine, in which the axis about which it swings is stationary, are more nearly analogous to those of a weather vane which points always toward the direction from which the wind blows. As has been stated above, the guide 47 is of very small cross section; and it should be understood that the blade of the knife is very narrow so as to make it capable of turning sharply when necessary. With the present machine provided with a knife of proper width it is possible to cut out square holes or even to turn corners the angles of which are less than ninety degrees.

Although the invention has been set forth in connection with a particular machine, it should be understood that the invention is not limited in the scope of its application to the particular machine shown and described. 70

Having thus described my invention, I claim as new and desire to secure by Letters Patent of the United States:

1. A machine of the class described, having, in combination, a support for a piece of stock, said support having an opening therein, a knife extending into said opening, and a reciprocating knife bar upon which the knife is revolvably mounted, the axis of the bar being in advance of the knife whereby 75 when the stock is moved against the knife, said knife presents its cutting edge in a direction opposite to that in which the stock is being moved.

2. A machine of the class described, having, in combination, a support for a piece of stock, said support having an opening therein, a knife extending into said opening, a reciprocating knife bar upon which the knife is revolvably mounted and with respect to the 80 axis of which the knife is offset whereby when the stock is moved against the knife, said knife presents its cutting edge in a direction opposite to that in which the stock is being moved, and a guide the axis of which 85 coincides with the axis of the knife-bar.

3. A machine of the class described, having, in combination, a support for a piece of stock, said support having an opening therein, a knife extending into said opening, a reciprocating knife bar upon which the knife is revolvably mounted and with respect to the axis of which the knife is offset whereby 90 when the stock is moved against the knife, said knife presents its cutting edge in a 95 direction opposite to that in which the stock is being moved, and means for gripping the stock at a point close to the edge of the knife.

4. A machine for operating upon appliquéd work, having, in combination, a support, a guide adapted to engage the edge of the pattern, a knife angularly movable about said guide, and means for reciprocating 100 said knife. 110

5. A machine for operating upon appliquéd work, having, in combination, a support, a guide adapted to engage the edge of the pattern, a presser foot having an opening in which said guide is located, a knife 120 angularly movable about said guide, and means for reciprocating said knife.

6. A machine for operating upon appliquéd work, having, in combination, a support provided with an opening therein, an auxiliary support of small cross section located in said opening, a knife angularly movable about said auxiliary support, and means for reciprocating said knife. 125

7. A machine for operating upon ap- 130

- pliqué work, having, in combination, a support provided with an opening therein, an auxiliary support of small cross section located in said opening, a knife angularly movable about said auxiliary support, a presser foot having an opening to receive said knife, and means for reciprocating said knife.
8. A machine for operating upon applique work, having, in combination, a support provided with an opening therein, a knife angularly movable about an axis which extends through said opening, the axis being located in advance of the knife, means for reciprocating said knife, and means for guiding said knife along the edge of the pattern as said work is moved over said opening.
9. A machine for operating upon applique work, having, in combination, a support provided with an opening therein, an auxiliary support of small cross section located in said opening, a guide adapted to engage the edge of the pattern, said guide being located in register with said auxiliary support, a knife extending into said opening and angularly movable about said guide and auxiliary support, and means for reciprocating said knife.
10. A machine for operating upon applique work, having, in combination, a support in the form of a thimble provided with an auxiliary support in the center thereof, a presser foot registering with the rim of the thimble and having a guide registering with the auxiliary support, a knife movable about the axis of said guide and auxiliary support, and means for reciprocating said knife.
11. A machine for operating upon applique work, having, in combination, a support in the form of a thimble provided with an auxiliary support in the center thereof, a presser foot registering with the rim of the thimble and having a guide registering with the auxiliary support, a knife movable about the axis of said guide and auxiliary support, and means for reciprocating said knife, said thimble being movable from and toward said foot and knife to permit the work to be placed over the thimble and to cause it to be pierced by the knife.
12. A machine for operating upon ap-

pliqué work, having, in combination, a support provided with an opening therein, an auxiliary support of small cross section located in said opening and having its upper operative end flush with the plane of said support, a skeleton presser foot the plane of the lower operative face of which is parallel to that of the support and spaced therefrom, a guide of small cross section arranged to coöperate with said auxiliary support and having its lower operative face spaced from said auxiliary support a distance less than that between the presser foot and the main support, and a knife freely revoluble about the axis of said guide and offset from said axis.

13. A machine for operating upon applique work, having, in combination, a support provided with an opening therein, an auxiliary support of small cross section located in said opening and having its upper operative end flush with the plane of said support, a skeleton presser foot the plane of the lower operative face of which is parallel to that of the support and spaced therefrom, a guide of small cross section arranged to coöperate with said auxiliary support and having its lower operative face spaced from said auxiliary support a distance less than that between the presser foot and the main support, and a reciprocating knife freely revoluble about the axis of said guide and offset from said axis.

14. A machine of the class described, having, in combination, a support for a piece of stock, said support having an opening therein, a knife extending through said opening, a knife bar upon which the knife is revolvably mounted and with respect to the axis of which the knife is offset, a shaft rotation of which causes reciprocation of said knife bar, means for raising and lowering said support, and means connected with said last-named means for applying power to and for withdrawing power from said shaft whereby when said support is lowered said knife comes to rest and when said support is raised said knife reciprocates.

In testimony whereof I have signed my name to this specification.

SAMUEL J. WENTWORTH.
